COMBUSTION APPARATUS

Ben Valjean, East Lansing, Mich., assignor to
 Motor Wheel Corporation, Lansing, Mich., a
 corporation of Michigan

Application January 2, 1937, Serial No. 118,867

2 Claims. (Cl. 158—91)

This invention relates to combustion apparatus and more particularly to apparatus of that character embodying a novel form of vaporizing pot type burner. The present application is 5 directed in part to subject matter disclosed in the copending application of Ben Valjean, Serial No. 736,509, filed July 23, 1934, now Patent No. 2,073,270, granted March 9, 1937.

The aims and objects of the present invention 10 will become apparent from the detailed description thereof when read in connection with the accompanying drawings, wherein:

Fig. 1 is a vertical sectional view of a heater embodying the present invention;

Fig. 2 is a sectional view taken on substantially the line 2—2 of Fig. 1;

Fig. 3 is an enlarged vertical sectional view of the burner forming a part of the heater shown in Fig. 1;

Fig. 4 is a fragmentary plan view of the baffle ring forming a part of the burner; and

Fig. 5 is an enlarged fragmentary sectional view of the burner illustrating an alternative method of attaching the baffle ring to the burner.

The heater shown in Fig. 1 includes an outer casing 10 surrounding a burner 11. The details of the burner are shown in Fig. 3. It consists of a generally frusto-conical pressed metal side wall 12 of substantially uniformly increasing 20 diameter from its bottom to its top. A pan like bottom wall 13 is secured to the lower extremity of the shell in a manner to form a fluid tight joint therewith, as by welding.

Adjacent its upper extremity, the shell 12 is 25 provided with a radially inwardly extending annular rib 14. Above the rib 14, the shell is provided with a radially outwardly extending rib 15. The rib 14 serves to support a centrally apertured top wall 16. The rib 15 is utilized in 30 securing the burner in the casing and also serves to secure a baffle 17 in position.

Baffle 17 is a centrally apertured disk made up of two separate sections 17a and 17b which are 35 secured to each other by cotter keys 18. The baffle is provided with depending legs 19 adapted to rest upon the top wall 16 and to space the baffle therefrom. The radially outer edge of each of the legs 19 is formed with a projection 19a adapted to be inserted in the rib 16, to lock the 40 baffle in position.

In installing the baffle 17, the separate sections are inserted within the burner and then moved 45 radially outwardly so that the leg portions 19a extend into the rib 15. With the sections 17a and 50 17b in this position the cotter pins 18 may be

inserted in openings provided for that purpose. The baffle 17 is then securely locked in position in vertically spaced relation to the top wall 16.

An alternative method of securing the baffle ring 17 in position is shown in Fig. 5. As there 5 shown the projections on legs 19a are eliminated and the upper surface of the baffle 17 is formed of reduced thickness about its periphery as shown at 17c. The upper edge of burner side wall 12 is flanged radially inwardly as indicated at 12a. 10 The sections 17a and 17b of the baffle are installed separately and after the reduced peripheral portions 17c of the baffle sections have been inserted under the flange 12a, the cotter keys 18 may be 15 installed and the baffle is securely locked in place.

The tapered side wall 12 of the burner is provided with a plurality of primary and secondary air inlet openings 20 and 21, respectively. The primary air inlet openings 20 are located beneath top wall 16 and the secondary air inlet openings 20 20 21 are located above the top wall 16 and below the baffle 17, being formed in the lower portion of rib 15 so that air enters therethrough in a direction toward baffle 17. The size and spacing of these air inlet openings are important. Within 25 reasonable variations, it is essential that the primary air inlet openings 20 be of relatively small cross sectional area and spaced substantially uniformly, both vertically and horizontally. Secondary air inlet openings 21 should also be 30 spaced uniformly and are preferably fewer in number but relatively larger than the primary openings 20. It is essential, for best results, that the size and spacing of all of the air inlet openings be such that the total cross sectional 35 area of the primary air inlet openings is substantially greater than the total cross sectional area of the secondary air inlet openings. In other words, best results are obtained in the operation of the burner if a greater volume of air 40 is introduced into the burner through the primary air inlet openings than through the secondary air inlet openings.

In the burner shown the side wall 12 is approximately 7½ inches high and varies from 45 a diameter of approximately 10¼ inches at the bottom to a diameter of approximately 12 inches at the top. There are 26 holes in each row of primary air inlet openings 20, spaced as shown. These holes are all of the same size except the top 50 row, which are slightly larger than the others. The total area of the primary air inlet openings is approximately .8 square inch. There are 52 holes in the single row of secondary air inlet openings spaced as shown. The total area of the 55

secondary air inlet openings is approximately .5 square inch.

The size of the central openings in the top 16 and the baffle 17 are also of substantial importance in the burner shown, the diameter of the opening in the top wall 16 is approximately 6 inches and the diameter of the opening in baffle 17 is approximately 9 inches.

The burner side wall 12 is preferably formed from a strip of relatively light gauge sheet metal. The holes 20 and 21 may be punched or drilled in the metal while it is in strip form and the strip afterwards coiled to the shape shown. The ribs 14 and 15 are preferably formed after the strip has been coiled and permanently secured in its final shape. The bottom wall 13, the top wall 16, and the baffle 17 are all preferably formed of cast iron, although the bottom wall may be formed of relatively heavy gauge steel if desired.

20 The burner 11 is secured to casing 10 as shown in Fig. 1. The casing is provided with a radially inwardly extending rib 22 intermediate its extremities. The burner is arranged within the casing with the radially outwardly extending rib 15 of the former contacting the rib 22 of the casing. The burner is secured in this position by a screw threaded device 23 mounted in a bracket 24 extending across the bottom of casing 10. Suitable sealing means, such as asbestos or the like, is placed between the cooperating ribs 15 and 22 to provide an air tight joint therebetween.

Bracket 24 does not completely close the bottom of casing 10 and is secured in position by the same securing elements 25 which secure the supporting legs 26 to the lower extremities of the casing 10.

The lower portion of casing 10 is open to the atmosphere and forms an air compartment 27 surrounding burner 11. The upper portion of the casing 10, above burner 11, serves as a combustion chamber 28. A top wall 29 is provided for the upper extremity of casing 10. Combustion chamber 28 is connected with a chimney 30 by an exhaust pipe 31. Pipe 31 is provided with a draft regulator 31a. Casing 10 is provided with a door 32 in its upper part which provides access to the interior of the combustion chamber 28.

By reason of the tapered or frusto-conical form of burner 11 it is possible to use a single cylindrical casing 10 of substantially uniform diameter, as a combustion chamber and an air compartment for the burner. As shown, the diameter of the casing is substantially no greater than the maximum (top) diameter of burner 11. The air compartment 27 constitutes the annular space between the side wall of the burner 11 and that portion of casing 10 below the rib 22 formed therein.

60 Oil is delivered to the lower portion of burner 11 from a source of supply, not shown, through a supply pipe 33. A conventional form of regulating valve shown diagrammatically at 34 in Fig. 1 is associated with pipe 33. Air is drawn into the burner 11 through the openings 20 and 21 by means of the draft produced by chimney 30. For this purpose it is necessary that air compartment 27 be open to the atmosphere. By reason of the air tight joint between ribs 15 and 22, the only air which is introduced into the apparatus enters the apparatus through air inlet openings 20 and 21.

A characteristic and valuable feature inherent in the present apparatus is its capacity to burn varying amounts of oil and thereby produce a

greater or lesser amount of heat. It has a wide range of operation.

The burner is designed to permit the maximum amount of premixing of air and oil vapors at all stages of operation, thus assuring clean and efficient combustion. This is made possible by localizing the zone of combustion away from the surface of the liquid oil in the burner. That result is in turn obtained by the proper size and spacing of the air inlet openings 20 and 21.

It is well known in the art to which this invention relates that it is desirable to avoid a concentration of air at any point in the apparatus. It is also well known that adequate provision must be made to prevent explosions which would result if the combustion flame became extinguished when the apparatus is full of combustible oil vapors.

Heretofore, it has been the practice to provide against this explosion hazard by introducing a substantially excessive amount of secondary air in order to maintain fire in the apparatus regardless of any excess of fuel vapors that might be generated. So far as applicant is aware, he was the first to discover that such an excessive amount of secondary air is not necessary to overcome this explosion hazard providing a proper form of apparatus is employed. The present invention eliminates the necessity of employing an undesirable amount of excess secondary air in order to attain the necessary insurance against explosions.

As previously stated, the volume of secondary air introduced into the apparatus disclosed in this application is substantially less than the volume of primary air utilized. This makes for more efficient operation than where a greater amount of secondary air is used.

Unlike the prior art devices, applicant directs the secondary air toward, and in part at least against, the baffle ring 19. Consequently, the velocity of the secondary air is substantially decreased. At the same time the secondary air is directed toward the central opening in top wall 16 through which the oil vapors flow. Thus, there is always present adjacent this opening a relatively large volume of relatively slow moving air which contacts the relatively fast moving oil vapors arising from the burner.

The difference in velocity of the air and oil vapors assure combustion (flame) adjacent the opening in top wall 16 whenever oil vapors pass therethrough regardless of the quantity or speed of such vapors. Any vapors in excess of that which will mix with the air present to produce combustion, pass on out of the combustion chamber to the chimney, without danger of causing an explosion in the apparatus. Thus applicant has eliminated the possibility of explosion due to excess of oil vapors without adversely affecting the efficiency of his apparatus by utilizing an excess of air.

The complete operation of the apparatus shown and described is as follows:

By suitable adjustment of valve 34, oil is admitted to burner 11. The oil is ignited by a flame introduced into the apparatus through the door 32 or by a conventional form of pilot device. Initially combustion occurs on the surface of the oil, the necessary air being supplied by primary air inlet openings 20. As soon as sufficient heat is developed the available oil is vaporized and combustion occurs away from the surface of the oil. This may be due either to an insufficient supply of air, or other reasons not fully understood.

At any rate, the zone of combustion does move farther upward and away from the oil as the rate of vapor generation increases. Of course, as soon as the zone of combustion is above any of 5 the primary air holes 20, the air entering through those particular holes is being premixed with the oil vapors in advance of combustion.

At all times after the initial lighting, there is sufficient heat produced by the flame to evaporate the oil introduced substantially as fast as it is admitted up to a predetermined maximum. When the burner is operating at or near this predetermined maximum rate of vaporization substantially all of the combustion (flame) is 15 localized above the top wall 16, and substantially all of the air admitted through primary air inlet openings 20 is utilized for premixing, the air admitted through secondary air inlet openings 21 serving to localize the lower limit of the zone 20 of combustion adjacent the top wall 16. By suitable regulation of valve 34 the lower limit of the zone of combustion may be fixed either immediately over the surface of the oil, above the top wall 16, or in an intermediate locality.

25 The scope of the invention is indicated in the appended claims.

I claim:

1. Combustion apparatus comprising a burner of the vaporizing pot type having a tubular side wall provided with an integral radially outwardly extending annular rib adjacent the top thereof, a plurality of air inlet openings formed in said rib, a centrally apertured top wall positioned within the burner below said air inlet openings, and a centrally apertured baffle ring positioned above said rib, the opening in the baffle ring being substantially larger than and arranged in alignment with the opening in the top wall, the baffle ring and said air inlet openings being constructed and arranged so that the axes of said air inlet openings intersect the plane of the baffle ring at a substantial angle, whereby the air admitted through said openings impinges against the baffle ring. 5 10 15

2. Combustion apparatus as defined in claim 2, wherein the side wall of the burner is of frusto-conical shape and the external rib is located in the region of the greatest diameter of the side wall. 20
